UNITED STATES PATENT OFFICE.

FRANK J. ROBINSON, OF PETERSBURG, ILLINOIS, ASSIGNOR OF ONE-HALF
TO D. M. BONE, OF SAME PLACE.

BED-BOTTOM.

SPECIFICATION forming part of Letters Patent No. 296,708, dated April 8, 1884.

Application filed September 8, 1883. (No model.)

To all whom it may concern:

Be it known that I, FRANK J. ROBINSON, of Petersburg, in the county of Menard and State of Illinois, have invented an Improved 5 Bed-Bottom; and I do hereby declare that the following is a full and exact description thereof, reference being had to the accompanying drawing, making part of this specification, and representing a top view of my improved bed- 10 bottom.

In the drawing, A A represent a set of bed-springs in place, and B B the slats on which they rest. The arrangement of these parts is as usual or as desired, and the outer springs 15 are secured to a rim or border-band, C, made of rattan, as shown; or the border-springs may each be connected at the outer edge by coiled springs, with the sides and ends of the box-frame of the bed-bottom.

20 My improvement consists in the peculiar method of connecting the springs A A at the top diagonally by means of two spiral springs, D D, each bent in the middle into a V form, as shown, and the two simply looped together, 25 as at a. The spring portions of each spring are at the two ends, and between these two spring or coiled portions there is a single-wire connection at a, forming the apex of the V-shaped entire spring, sufficient in length to 30 loop freely with the adjacent spring. Each of these springs is connected at its ends to two adjacent springs, A A, and the two springs looped together thus connect four adjacent bed-springs. Additional pairs of looped springs 35 connect to every four adjacent springs in a

row across the bed-bottom, and parallel rows are thus formed to compose the whole bed-bottom. By this connection diagonally between the bed-springs, free joints are formed in line along the loop-connections a a, rendering this bed-bottom especially elastic and flexible, and giving every bed-spring perfect freedom, each independent of all the others, while the bed-springs are all held in proper and upright positions, and when these free joints run 40 parallel with the supporting-slats a folding bed may be readily formed thereby. For smaller and cheaper beds, these diagonally-arranged looped springs are a sufficient connection for the bed-springs; but for the largest 45 and best beds I add spiral springs E E, to connect the bed-springs, at their nearest points, in directions both lengthwise and crosswise of the bed-bottom.

I claim as my invention—

55 In a bed-bottom, the V-shaped springs D D, each consisting of two coiled portions united by a single wire, forming the apex of the spring, looped together in pairs at their apices, in combination with the bed-springs A A, and means for supporting the said bed-springs, substantially as and for the purpose herein specified.

The foregoing specification signed by me this 27th day of August, 1883.

FRANK J. ROBINSON.
